UNITED STATES PATENT OFFICE.

JOSEPH LEWIS, OF CHICAGO, ILLINOIS.

BICYCLE.

SPECIFICATION forming part of Letters Patent No. 286,835, dated October 16, 1883.

Application filed September 10, 1883. (No model.)

To all whom it may concern:

Be it known that I, JOSEPH LEWIS, a subject of the Queen of Great Britain, residing in Chicago, in the county of Cook and State of Illinois, have invented a new and useful Improvement in Bicycles, of which the following is a specification.

Bicycle-riders are subject to a class of accidents known as "headers," and usually caused by running against obstacles. In them the rider is commonly thrown forward head foremost, with his machine on his back, and as he is unable to jump or otherwise clear himself from his machine when they occur, by reason of the rigid handles used for steering, he is obliged to submit to an ugly fall with the machine. Serious injury to the person is often caused in this way.

The object of the present invention is to obviate this danger to the rider, and it is accomplished by constructing the steering-handles with a joint at the steering-post in such manner that they are perfectly rigid for steering purposes, and yet, in case of a header, the thighs of the rider will strike them in such a way as to instantly open them forward and clear the way for him to drop on his feet, free of the machine.

The invention will be more fully understood from the following description and accompanying drawings, wherein—

Figure 1 is a front view of my improved bicycle-handles. Fig. 2 is a bottom view, and Fig. 3 a side elevation, of the same. Fig. 4 is a section upon the line 4 4, and Fig. 5 a section upon the line 5 5, of Fig. 1. Fig. 6 shows a modified form of the invention, partly in section.

In the drawings, A represents the steering-post; A', a bracket attached thereto and carrying handles, which are represented by B B'. At their adjacent ends the handles are furnished with metal socket-pieces b b', which are hinged together by a horizontal pivot, C, passing through the same and secured in the front and rear plates, D D', which form a part of or are rigidly attached to the bracket A'. These plates transmit the strain caused by the steering to the bracket and post, and of course

are made strong enough for all the contingencies arising in such service. The plate D' may be separate from or integral with the horizontal sleeve d, through which the projection a' of the bracket A' passes, and it, together with the plate D and said sleeve, forms a head, or boxing for the joint of the handles. Preferably the handles are kept in the horizontal position by the engagement therewith of some sort of a yielding lock device. The form of this device which I prefer consists of tapering points E, projecting into corresponding recesses, e, in the handle-sockets, said points being kept in such engagement by the springs E', secured upon the front plate. These spring-points may of course, by reason of their shape, be forced out of engagement whenever any unusual force is applied to the handles in the direction in which the latter are intended to yield. As it is obvious that other forms of locking-springs may be employed for this purpose, I do not wish to be limited to the form just described. Another form is shown in Fig. 6. In this modification the socket ends of the handles are provided with triggers F, engaging with the part d by means of lips f, and yieldingly held in such engagement by the springs F', and the handles are released, so they may swing upon their pivot, by the thighs of the rider coming against the triggers and freeing them from the bracket.

The operation of the device is as follows: When the rider meets with a header and is thrown forward, his limbs come in contact with the under side of the handles and exert power thereon in the direction in which their hinge allows them to open, so that they move into a parallel position. This permits the rider to free himself in an instant from all entanglement with the machine. Of course the rider may turn the handles on the hinge 90° by his hands if he has presence of mind to do so. The dotted lines in Fig. 1 show the handles partially opened, and in the same figure the outlines of the metal socket ends of the handles are clearly shown by similar lines.

Being rigid, except in the direction in which the rider's limbs strike them in headers, my improved handles are equally efficient for

steering as the former construction, and it is obvious they may be easily adapted to any form of steering-post, and that the construction of the joint may be varied in many ways.

5 I claim—

1. In a bicycle, the steering-handles hinged at the steering-post, substantially as and for the purpose specified.

2. In a bicycle, the steering-handles hinged at the post and provided with yielding locking devices, substantially as specified.

JOSEPH LEWIS.
